UNITED STATES PATENT OFFICE.

JULIUS WESTERLUND AND CARL MARD, OF BIRMINGHAM, ALABAMA.

ROTARY ENGINE.

No. 903,036.

Specification of Letters Patent.

Patented Nov. 3, 1908.

Application filed April 1, 1908. Serial No. 424,530.

To all whom it may concern:

Be it known that we, JULIUS WESTERLUND and CARL MARD, citizens of Finland, and subjects of the Czar of Russia, residing at 5 Birmingham, in the county of Jefferson and State of Alabama, have invented new and useful Improvements in Rotary Engines, of which the following is a specification.

This invention relates to rotary engines, 10 the object of the same being to provide a simple, effective and practical engine of the class described adapted to be driven by fluid pressure such as steam, air or gas, the engine being especially adapted by means of 15 the construction hereinafter described to maintain a practically continuous torque on the shaft which delivers the power of the engine.

A further object of the invention is to so 20 combine and arrange the parts of the engine that the engine, as a whole, is capable of being easily reversed thus adapting the engine to drive in either direction.

The invention also has for its object to 25 provide novel means for mounting the cylinder and the disks and pistons thereof in such manner as to reduce the friction as far as possible and provide for the automatic lubrication of the parts which are subjected to the 30 greatest wear.

A further object of the invention is to provide novel means for producing fluid tight joints between the cylinder and moving parts contained therein to prevent leakage 35 around the joints.

With the above and other objects in view, the nature of which will more fully appear as the description proceeds, the invention consists in the novel construction, combination 40 and arrangement of parts as hereinafter more fully described, illustrated and claimed.

In the accompanying drawing:—Figure 1 is a horizontal diametrical section through a rotary engine constructed in accordance with 45 the present invention. Fig. 2 is a vertical cross section through the same on the line 2—2 of Fig. 1, looking in the direction of the arrows. Fig. 3 is a similar section taken on the same line but looking in the opposite direction. Fig. 4 is a diametrical section through one of the piston carriers or disks. Fig. 5 is a plan view of the valve sleeve. Figs. 6, 7, 8 and 9 are cross sections through the valve sleeve taken on the lines 6—6, 7—7, 50 8—8 and 9—9, respectively, of Fig. 5. Fig. 10 is a detail section through one of the

disks, showing one of the outer packing blocks or strips thereof. Fig. 11 is a cross section taken at right angles to Fig. 10 illustrating the same feature. Fig. 12 is a plan view of one of the packing blocks partly broken away in section. Fig. 13 is an inner end view of the end bearing adjacent to the reversing mechanism. Figs. 14 and 15 are diagrammatic views illustrating different 60 positions of the parts during the cycle of operation. Fig. 16 is a sectional view of a modified form of reversing lever and connections.

Referring to the drawings, 1 designates 70 the shaft of the engine, the same being stationary at all times. The said shaft is hollow or tubular, being provided with a central longitudinal bore 2 and having live steam ports 3, 4, 5 and 6 leading outward therefrom and in the preferred embodiment of the invention, arranged in a longitudinal series or in longitudinal alinement with each other as shown in Fig. 1.

Fitting around the tubular shaft 1 is a 80 rotary valve sleeve 7 which is provided at one end with a flange 8, the latter being cut away for a portion of its circumference as illustrated in Figs. 6 to 9 inclusive to provide oppositely arranged shoulders 9 and 10, the purpose of which will hereinafter appear. The flange 8 abuts at its outer surface against a corresponding abutment flange 11 formed on the end of the shaft 1 while beyond the flange 11 the shaft is provided with a reduced extension 12 which is fixedly connected by means of a key 13 to a bearing head 14 in the form of a disk which works in a corresponding recess in one of the heads 15 of a multiple cylinder, 85 the opposite head of which is indicated at 16. The bearing head 14 forms a journal upon which the cylinder comprising the heads 15 and 16 revolves and it will be noted that the cylinder has an axis eccentric to 90 the axis of the shaft 1, the degree of eccentricity being governed by the position of the bearing head 14 with respect to the shaft 1 as indicated at right hand end of Fig. 1. The head 15 is provided with a central driving shaft 17 which is keyed into the head 15 as shown at 18 so that the rotary motion of the cylinder 15 is imparted to the shaft 17 from which the power may be belted or taken off in any approved manner.

The cylinder at its opposite end is provided with a relatively large bore in which

is fitted a bushing 19 which revolves upon the inwardly extending cylindrical part 20 of an end bearing 21 which may be in the form of a pedestal 22. The cylinder is supported at its opposite end by mounting the shaft 17 in a bearing 23 which may also be carried by a pedestal. The bearings 21 and 23 may be connected to a suitable base or bed plate upon which the engine, as a whole

10 is supported.

15 24 designates a packing ring let into a recess in one end of the cylinder to form a fluid tight joint between said end of the cylinder and the adjacent bearing 21. The head 16 of the cylinder is also provided with teeth 25 preferably of the worm-type to enable a suitable governor to be geared to the rotary cylinder of the engine. This governor is not shown.

20 The cylinder is of sectional construction as best illustrated in Fig. 1, wherein it will be understood that the head 15 is provided with an inwardly extending flange 26 and the head 16 is provided with a corresponding inwardly extending flange 27. Between the flanges 26 and 27 there is arranged an intermediate section 28 of the cylinder and all of said parts are connected to form a multiple cylinder by means of bolts 29 which

30 are inserted through circumferential flanges 30 with which each of said parts is provided.

35 The multiple cylinder illustrated in Fig. 1 comprises four chambers or cylinders and in the preferred embodiment of the invention, the intermediate section 28 is provided with an inwardly extending wall 31 while the walls 32 and 33 lying at opposite sides of the wall 31 are formed of separate rings or annular plates as shown, the same being 40 clamped and firmly held between the flanges 30 by means of the bolts 29. In this way the cylinder as a whole is divided into a plurality of compartments or individual cylinders in which the piston carrier or disks and 45 the pistons carried thereby operate. A piston carrier or disk is employed in connection with each of said compartments or individual cylinders, as shown in Fig. 1 and by reference to Figs. 1 and 2 it will be seen that 50 each of said disks indicated at 34 is mounted directly on the valve sleeve 7. Adjacent to its periphery each disk is provided with a cylindrical socket 35 in which is mounted an oscillatory cylindrical plug 36 having a slot 55 37 therein through which slides the inner portion of a piston 38 the outer end of which is fastened to the cylinder by securing the outer end of said piston in a groove or recess 39 formed in the inner wall of the cylinder 60 as shown in Figs. 1 and 2, the side edges of said piston fitting in grooves 40 in the adjacent inner surfaces of the side walls of the cylinder, as shown in Fig. 1, thus preventing leakage of the steam or other expansive fluid past the piston. Just inside of the

cylindrical recess 35, each disk is provided with a cavity 41 to receive the inner end of the piston 38 and admit of the inward and outward movements thereof and also the lateral or swinging movement of the inner 70 end of the piston as indicated in the diagrammatic views, Figs. 14 and 15. It will thus be seen that the piston is carried by the cylinder and as it has a sliding connection with the adjacent disk, the latter is also carried around with the piston and cylinder. It may be noted that where four disks and pistons are employed, they are arranged so that the pistons lie approximately 90° apart, this being done in order to obtain a practically continuous torque. At one side of the cylinder, each disk lies in close proximity to but preferably just out of actual contact therewith as indicated in Fig. 2. In its opposite sides each disk is provided with packing rings 42 which are let into the corresponding annular grooves therein as indicated in Fig. 1, openings 43 being formed between the recesses to receive expandible springs 44 which operate to press the packing rings 42 outward in contact with the adjacent walls of the cylindrical space in which the disk moves.

By reference to Figs. 2, 10, 11 and 12, it will also be observed that the disk is provided in its periphery with packing blocks 45 to obtain a fluid tight joint with the wall of the cylinder in the manner indicated in Figs. 2, 14 and 15, to prevent the steam or expandible fluid from passing to the opposite 100 side of the piston 38. As shown in Fig. 12, each block comprises overlapping sections 46 and 47, the overlapping sections being such as to break the joint between the sections while the sections are forced longitudinally in opposite directions by means of a spring 48 surrounding a guide or stay pin 49 connected to one of the sections. Each block is also pressed outwardly into a radial direction by means of a coil spring 50 set 110 in a recess in the disk and underlying said block as shown in Figs. 10 and 11. The side packing rings 42 are notched or slotted as shown in Fig. 2 so that the end portions of the blocks 45 project through the side packing rings and abut against the inner walls of the cylindrical space. This forms a fluid tight joint between the disk and the walls of the cylindrical space and prevents the steam or other fluid from getting by the piston. The degree of projection of the packing blocks 45 is such that at least two of said blocks always contact at the same time with the inner wall of the cylinder.

The live steam ports 51, 52, 53 and 54 of 125 the valve sleeve 7 are arranged 90° apart as shown in Figs. 5, 6, 7, 8 and 9 and opposite each live steam port there is arranged an exhaust port 55. By such arrangement of ports the steam is admitted through the 130

longitudinally alined ports 3, 4, 5 and 6 of the shaft 1 and admitted at regular intervals to the compartments of the cylinder, one after the other, and the exhaust steam 5 passing into the ports 55, enters circular channels 56 formed in the opposite sides of each disk and passes through openings 57 bored through the bodies of the disks until all of the exhaust enters a common exhaust 10 passage 57 in the head 16 of the cylinder and is deflected laterally outward through an exhaust orifice 58.

The end disk 34 is provided with a laterally projecting pin 59 which moves into contact with one of the shoulders 9 or 10 of the valve sleeve 7 according to the direction in which the engine is to be run and in accordance with the position of the reverse lever and connecting mechanism to be described.

20 In order to provide for reversing the engine a valve sleeve is provided at the end opposite the flange 8 with a toothed portion 60 and arranged adjacent thereto is a spur gear 61 mounted on a slidable shaft 62 journaled in the end bearing 21 as shown in Fig. 1. The hub of the pinion 61 is provided with a cone face 63 adapted to fit snugly against a corresponding seat as shown in Fig. 1 to prevent the escape of steam when 25 the pinion 61 is moved to the position shown in Fig. 1, where it is normally held by means of a spring 64 interposed between the outer wall of the end bearing 21 and the adjacent end of a reversing lever 65. The reversing 30 lever 65 is mounted fast on the shaft 62 and carries a thumb latch lever 66 the point of which is adapted to engage in one of a pair of openings 67 in a rack segment 68 secured to a fixed part of the machine. By moving 35 the latch 66 out of engagement with the rack segment 68, the lever may be swung through practically a half circle as indicated in Fig. 13 and by pushing the lever 65 inward at the same time and throwing the pinion 61 40 into engagement with the teeth 60, the valve sleeve 7 may be turned partially around the shaft 1 as far as the pin 59 will permit by coming in contact with one of the shoulders 9 or 10 thus reversing the inlet and exhaust 45 ports of the engine.

50 The head 15 of the cylinder is provided with an enlarged circular recess 69 to receive the flanges 8 and 11 of the shaft and valve sleeve and permit of the relative movement of said parts as the sleeve revolves.

By reference to Figs. 14 and 15 it will be seen that in Fig. 14 the live steam port of the valve sleeve is just coming into register with the corresponding port in the shaft the 55 latter being stationary. As these two ports pass by each other steam is admitted to the small space between the disk and cylinder and between the piston 38 and the packing block 45. The steam in expanding acts 60 against the piston 38 the cylinder and disk

together with the piston being driven in the direction indicated by arrows in said figures, wherein it will be seen that the space continues to increase thus providing for the expansion of the steam or other fluid. Under 70 the arrangement shown in the diagrammatic views, Figs. 14 and 15, 70 represents the inlet passage and 71 the exhaust passage of the disk, but it will be understood that when the reversing mechanism is manipulated, the ports 71 become the inlet ports while the remaining ports 70 carry off the exhaust.

In order to prevent the steam from passing along the sleeve 7 from one piston to another, packing rings 72 are inserted in the outer surface of the said sleeve as shown in Fig. 1. A packing ring 73 is also inserted in the end of the sleeve so as to bear against the flange 11 and a corresponding packing ring 74 is set into the opposite ring of the sleeve and arranged to bear against a collar 75 mounted fast on the shaft 1 as shown in Fig. 1.

Instead of the reversing lever arrangement shown in Fig. 1, the modified arrangement shown in Fig. 16 may be employed wherein it will be observed that the reversing lever 65' is provided with a hub 76 which passes through a bearing 77 connected with the end bearing 21, the shaft 92 being keyed into the hub 76 as shown so that the shaft 62 is caused to turn with the lever 65'. Pivotally connected to the lever 65' at the point 78 is a thumb 79 the inner end of which has a jointed connection at 80 with a collar 81 fast on the shaft 62, the spring 64 being interposed between said collar 81 and the bearing 21. Connected to the lever 79 is a latch 82 in the form of a pin adapted to enter either one of a pair of notches in the rack segment 83 for holding said lever in either of its two extreme positions, to effect the reversing of the engine as above explained. The disk being concentric with the shaft and the cylinder eccentric thereto the pressure of the steam against the piston will cause the cylinder to turn and as the disk and piston are attached to the cylinder, they are likewise caused to rotate simultaneously therewith. The piston being adapted to slide and also rock relatively to the disk, the leverage is increased progressively from the time that the steam enters the steam space thereby allowing the steam to expand fully 115 and get the full benefit of such expansion.

Having thus described the invention, what we claim is:—

1. In a rotary engine, a ported shaft, a disk concentric thereto and provided with steam ports leading from its center, a cylinder eccentric to said shaft, a piston rigidly attached to one of said parts and jointed to the other part, a ported valve sleeve upon which the disk is mounted, and means for 125 130

moving said sleeve to direct the steam to either of the disk ports.

2. In a rotary engine, a ported shaft, a disk concentric thereto and provided with steam ports leading from its center, a cylinder eccentric to said shaft, a piston rigidly attached to one of said parts and jointed to the other part, a ported valve sleeve surrounding said shaft and having the disk 10 mounted thereon, and means for shifting said sleeve to direct steam to either of the disk ports.

3. In a rotary engine, a ported shaft, a disk concentric thereto and provided with steam ports leading from its center, a cylinder eccentric to said shaft, a piston rigidly attached to one of said parts and jointed to the other part, a ported valve sleeve surrounding said shaft and having the disk 15 mounted thereon, and means for shifting said sleeve to direct steam to either of the disk ports including a pinion movable into and out of engagement with a toothed member on said sleeve.

25 4. In a rotary engine, a ported shaft, a disk concentric thereto and provided with steam ports leading from its center, a cylinder eccentric to said shaft, a piston rigidly attached to one of said parts and jointed to the other part, a ported valve sleeve surrounding said shaft and having the disk 30 mounted thereon, and means for shifting said sleeve to direct steam to either of the disk ports including a pinion movable into and out of engagement with a toothed member on said sleeve, and a reversing lever operatively connected with said pinion.

5. In a rotary engine, a ported shaft, a disk concentric thereto and provided with steam ports leading from its center, a cylinder eccentric to said shaft, a piston rigidly attached to one of said parts and jointed to the other part, a ported valve sleeve surrounding said shaft and having the disk 40 mounted thereon, and means for shifting said sleeve to direct steam to either of the disk ports including a pinion movable into and out of engagement with a toothed member on said sleeve, and means for shifting 45 and turning said pinion.

6. In a rotary engine, a ported shaft, a disk concentric thereto and provided with steam ports leading from its center, a cylinder eccentric to said shaft, a piston rigidly 50 attached to one of said parts and jointed to the other part, a movable valve sleeve adapted to direct steam to either of said ports, oppositely-arranged shoulders on said sleeve, and a projection on the disk with 55 which said shoulders co-operate.

7. In a rotary engine, a ported shaft, a

disk concentric thereto and provided with steam ports leading from its center, a cylinder eccentric to said shaft, a piston rigidly attached to one of said parts and jointed to the other part, a movable valve sleeve adapted to direct steam to either of said ports, a flange on said sleeve mutilated to form opposite shoulders, and a projection on the disk with which said shoulders co- 65 operate. 70

8. In a rotary engine, a ported shaft, a disk concentric thereto, steam ports leading from the center of said disk to the periphery thereof, a cylinder eccentric to said shaft, a piston rigidly attached to one of said parts and jointed to the other part, a movable valve sleeve adapted to direct steam to either of said ports, a bearing head concentric with the cylinder and eccentric to said shaft, and 75 a concentric bearing for said head in the cylinder. 80

9. In a rotary engine, a ported shaft, a disk concentric thereto, steam ports leading from the center of the disk outward to the periphery thereof, a cylinder eccentric to said shaft, a piston rigidly attached to one of said parts and jointed to the other part, a movable valve sleeve adapted to direct steam to either of said ports, and a bearing head 85 having an eccentric relation to said shaft and a concentric relation to the cylinder, the disk being recessed for the passage of the exhaust and said bearing head being exposed to the action of the exhaust. 90

25 10. In a rotary engine, a ported shaft, disks concentric thereto and provided with steam ports leading from the center outward, a sectional cylinder eccentric to said shaft, cylinder walls clamped between the meeting 100 edges of the cylinder sections, pistons rigidly attached to the cylinder and having a jointed connection with the disks, and a movable valve sleeve adapted to direct steam to the disk ports. 105

11. In a rotary engine, a ported shaft, a disk concentric thereto and provided with steam ports leading from its center, a cylinder eccentric to said shaft, a piston rigidly attached to one of said parts and jointed to the other part, side packing rings let into recesses in the disk, and expansible packing blocks extending across the periphery of the disk and intersecting said rings. 110
